Attorney

UNITED STATES PATENT OFFICE

JOSEPH P. EISENMANN, OF KAYLOR, SOUTH DAKOTA

FENCE POST

Application filed May 27, 1930. Serial No. 456,253.

The present invention relates to fence posts and more particularly to a fence post upon which the fence wire may be removably secured.

5 An object of this invention is to provide a post which may be readily driven into the ground in the conventional manner and which is so constructed that any size of fence wire may be readily mounted thereon, the 10 device including means for locking the wire upon the fence.

Another object of this invention is to provide a post of this character with a removable key or locking bar which is adapted to be 15 slidably mounted on the post so as to secure the fence wire thereupon.

A further object of this invention is to provide a fence post of this character having a suitable anchoring member adjacent the bottom 20 thereof which is adapted to anchor the post in the ground, the anchoring portion being driven into the ground with the post.

The above and various other objects and advantages of this invention will in part be 25 described in and in part be understood from the following detailed description of the present preferred embodiment, the same being illustrated in the accompanying drawing wherein:—

30 Figure 1 is a fragmentary detail front elevation partly in section of a post constructed according to the preferred embodiment of this invention;

Figure 2 is a side elevation taken on the line 2—2 of Figure 1;

Figure 3 is a sectional view taken on the line 3—3 of Figure 1; and

Figure 4 is a top plan view of the anchoring member.

40 Referring to the drawing wherein like numerals of reference designate corresponding parts throughout the several views, the numeral 10 designates generally the body of a post which is preferably of substantially low construction and is provided at the lower 45 end portion thereof with a restricted end 11 which is adapted to be driven into the ground. The post 10 may be formed by bending a strip of metal into substantially cylindrical construction, the free ends of the metal being

notched as at 12 so as to provide a plurality of arms or lugs 13, the lugs 13 being adapted to be bent inwardly and the lugs on one marginal edge of the strip being positioned in spaced relation to the lugs of the opposing edge.

55 The upper end of the post or body 10 is preferably formed in substantially cylindrical form as at 14 so as to provide a driving head for the post, and the arms 13 are adapted to extend outwardly from the body so as to provide a vertically disposed key-way for 60 removably receiving a locking key or member 15.

65 A fence wire 16 of any desired character is adapted to engage the post in the desired notches 12 thereof resting upon the upper edge portions of the arms 13 and when so positioned the locking bar or key member 15 which is provided with a handle or the like 70 17 at the upper end thereof is slid or moved downwardly through the key-way 18 formed by the inwardly extending members 13, the locking member being interposed between the members 13 and the fence wire so that 75 the wire will be positioned in the notches 12 and be held by the inner face or surface of the locking member 15.

80 An anchoring plate or member 19 having depending members 20 is positioned on the lower end of the post 10 and is adapted to be driven into the ground when the restricted point 11 is driven into the ground. The depending bars 20 prevent circumferential 85 movement of the post 10 and also serve to hold the post in vertically disposed position in the ground.

90 In the use of this device, when it is desired to mount a fence wire upon the post the locking member 15 is preferably removed from the body 10 by withdrawing it upwardly therefrom whereupon the point 11 may be positioned in the ground and the post driven therein in the conventional manner. When 95 the post has been properly set in the ground the fence wire 16 may be mounted on the post in the desired notches 12 so that the bottom of the fence will be in the desired position with respect to the ground.

100 It will be obvious from the foregoing that

notwithstanding the depth of the post in the ground the fence wire may be positioned on the post in the desired notches 12 so that the fence will be in horizontal position with respect to the surface of the ground.

5 When the wire 16 has been positioned in the desired notches 12 the key or locking member 15 may be inserted in the upper end of the post and moved downwardly so that the outer surface of the key 15 will engage against the inwardly extending members 13 and the inner surface of the key member will engage against the fence wire so as to force the fence wire against the body of the post 10 and prevent removal of the fence therefrom.

15 It will be obvious from the foregoing that an exceedingly simple and practical fence post has been disclosed by means of which the fence wire may be easily and securely positioned thereupon and that when it is desired to remove the fence wire from the post it is not necessary to pull the post out of the ground or to injure the fence wire in any manner inasmuch as the wire may be readily 20 removed by moving the key member 15 upwardly which will release the wire and permit its removal from the notches 12.

25 It is, of course, understood that various changes and modifications may be made in the details of construction and design of the above specifically described embodiment of the invention without departing from the spirit thereof, such changes and modifications being restricted only by the scope of 30 the following claims.

35 What is claimed is:—

1. In a fence post, a plurality of complementary guide and wire supporting members struck from the body of the post, and an elongated wire locking key slidably engaging said guide members whereby to releasably secure a wire fence upon said guide members.

40 2. In a hollow post structure, means for removably securing a wire fence thereto, said 45 means comprising a plurality of longitudinally spaced complementary L-shaped arms integrally formed with said post and having one leg thereof disposed laterally of the longitudinal axis of the post whereby to provide guides outwardly of the body of the post, and an elongated key member engaging said guides whereby to removably secure the wire fence upon said arms.

50 In testimony whereof I hereunto affix my 55 signature.

JOSEPH P. EISENMAN.
